UNITED STATES PATENT OFFICE.

MAYNARD T. JOY, OF NEW YORK, N. Y.

REGISTER-GUIDE AND GRIPPER.

1,305,904.

Specification of Letters Patent. Patented June 3, 1919.

Application filed March 9, 1918. Serial No. 221,541.

To all whom it may concern:

Be it known that I, MAYNARD T. JOY, a citizen of the United States, and a resident of the city of New York, borough of Manhattan, in the county and State of New York, have invented a new and Improved Register-Guide and Gripper, of which the following is a full, clear, and exact description.

10 This invention relates to guides for printing presses and has for an object the provision of an improved combination guide and gripper for guiding paper to a correct position and holding the same in said position.

Another object in view is to provide a gripper arm with an extending portion to act in the usual capacity of an arm, and a reduced portion together with a movable 20 guide, the parts being so arranged that when the gripper arm moves to a position on the platen during the printing operation the guide will automatically move for shifting properly the paper on the platen.

25 A further object in view is to provide a movable guide formed in such a manner as to push a piece of paper on the platen at first rapidly and then slowly until the paper has been moved to the correct position for 30 printing.

Another object is the provision of an adjustable guide formed with gripping means for engaging the paper so as to prevent any momentum thereof when being moved to the 35 correct printing position.

In the accompanying drawings:

Figure 1 is a fragmentary perspective view of a platen and gripper bar together with an embodiment of the invention applied thereto.

40 Fig. 2 is a top plan view of the guide and associate parts shown in Fig. 1.

Fig. 3 is a view similar to Fig. 2, but showing the parts in their operated position.

45 Fig. 4 is a sectional view through Fig. 2 on line 4—4.

Fig. 5 is a sectional view through Fig. 3 on line 5—5.

50 Referring to the accompanying drawings by numerals, 1 indicates a platen of any ordinary kind on any suitable form of press said platen being provided with a lower guide 2 for properly supporting the paper 3 when placed in position. Associated with

55 the platen 2 is a gripper bar 4 of any usual

preferred structure, said gripper bar having a base 5 clamped thereto in any suitable way, as for instance by the bolt 6, said base being preferably formed integral with the 60 gripper arm 7, which arm extends partly across the platen 1 when the press is closed. The arm 7 is offset slightly at 8 for clearing part of the movable guide 9. This movable guide is formed as more particularly shown 65

in Figs. 2 and 3 and is connected to the base 5 of the gripper arm 7 so as to be automatically operated as the gripper bar and arm move in the usual way. A hinge 10 is mounted on the base 5, said hinge acting to 70

connect the power rod 11 with base 5 so as to move the power rod at the proper time. The frame 12 of the guide 9 preferably consists of a flat piece of metal having an offset 13 at one end which is formed into 75

part of a hinge, or as a plate 14 connected therewith, formed with upstanding ears through which the pintle 15 passes, said pintle also passing through a pair of ears 16 connected to the cross-bar 18, which 80 cross-bar in turn is riveted or otherwise secured to the base 5. It is, of course, understood that base 5 could be formed with ears and the frame 12 with ears independent 85

of the extra bars 14 and 18 without departing from the spirit of the invention, provided these ears were formed so as to accommodate the pintle 15 and a spring 17. The pintle 15 is preferably in alignment with the journal pin 18' of bar 4 so that 90

when the bar 4 moves frame 12 will not move though the hinge 10 will move and will consequently move the rod 11 longitudinally. In this way the frame 12 is connected through the base 5 to gripper bar 4, and 95

movement is given to the rod 11 so that the parts hereinafter fully described will be operated for properly shifting the sheet 3 as the press is operated. A guide 19 for rod 11 is preferably rigidly secured to the 100 frame 12 and is provided with an overhanging hook section 21 whereby the rod 11 must move back and forth in a given path so as to operate the toggle levers 22 and 23. Lever 22 is preferably double so 105

that lever 23 may be journaled therebetween, and in that way give a direct thrust without any side movement. The lever 23 is pivotally mounted at 24 on a suitable projection 25 and secured in any suitable way 110 to frame 12, or formed integral therewith. The lever 22 is pivotally connected to an

extension 26 on the slide 27 which slide is 5
slidely mounted between the guide plates 28 and 29 and between the end of the frame 12 and end-block 30. These guiding members 10
act to cause slide 27 to move back and forth at right angles to the frame 12. A spring holding plate 31 is rigidly secured in any suitable manner, as for instance by screw 32, to the end-block 30, said spring 15
holding plate having rigidly secured thereto a paper retaining spring 33 which is bent in one direction at 34 and the opposite direction at the end 35 so that when the pusher guard 36 is moved toward paper 3 for shifting the position thereof the end 35 will 20
gradually move downwardly and engage the paper so that its final position will be as shown in Fig. 5. In this way the pusher guard 36 will move the paper and the spring 25
acting through the curved end 35 will prevent any momentum of the paper so that the movement of the paper will stop immediately upon the stopping of the guide. This question of momentum has also been 30
taken care of by the arrangement of the toggle levers 22 and 23 which at first move the slide 27 and the guide 36 rapidly, but which gradually slows down until it stops at its extreme outer movement. The pusher 35
guide 36 is provided with an overhanging bifurcated extension 37 which accommodates the screw 38 fitted into slide 27 whereby the pusher may be adjusted independently of the other parts and thereby 40
take care of any slight difference in the position of the paper 3 without molesting the clamping bolt 6. It is, of course, understood that the clamping bolt 6 may be removed and the parts adjusted longitudinally of the bar 45
4 to any desired extent, though where a small or fine adjustment is desired the movement of the extension or plate 37 after alining screw 38 is usually necessary. In using the device the paper is always fed 50
downwardly against the guide or guides 2 and also against the movable guide 9. Usually it is comparatively easy to cause the lower edge of the paper to rest on the guide or guides 2, but it takes some considerable 55
skill and also time to properly fit the end edge of the paper against the end guide. In the present instance if the paper engages the lower guides the pusher guide 36 will move the paper over to the correct position 60
to cause a proper registry, and usually if the paper is not quite correctly engaging the lower guides the lateral movement will cause the paper to act under gravity and engage these guides so that a more or less inexperienced person may be used to feed the paper and exact registry secured. Where printing 65
is done in a single color often times exact registry is not essential, though always desirable. In printing in colors however an exact registry is not only desirable, but es-

sential, and it is also extremely desirable to keep the press going at a certain speed in order that a proper quantity of ink may be supplied for each impression and a movement of the feeder. The guide 9 will always 70
engage the edge of the paper as the pusher 36 is preferably formed with a slightly sharpened edge 39 as shown in Fig. 5 and the curved end 35 will prevent any momentum created in the paper even though 75
the press is running at comparatively high speed. Referring to Figs. 4 and 5 it will be seen that the spring 36 extends through a suitable notch 40 centrally of the pusher 80
36. In addition to accomplishing the desired result of preventing momentum in the paper the spring by its shape and action will flatten or straighten out paper that is curved somewhat or bulged somewhat when inserted. In accomplishing this result it will be noted that the spring extends over the paper and is pressed downwardly against the paper by the pusher 36 so that the spring will properly straighten the paper out as well as to engage the same in 85
such a way as to prevent momentum, all of which is done quickly, easily, and automatically, and in proper timed relationship to the speed of the press.

What I claim is:

1. A combination gripper arm and guide comprising a gripping arm connected with the gripper bar of a printing press, and a guide hinged to the gripper arm, said connection being in the form of two hinges with 100
one hinge offset from the other whereby the last mentioned hinge will produce a movement, a rod connected with the last mentioned hinge, a pusher member, a toggle connected with said pusher member and said 105
rod, and means coacting with the pusher member for preventing the pusher member from producing a momentum in the paper engaged by the pusher member.

2. A gripper arm and guide comprising 110
an arm structure connected with the gripper arm, a guide structure including a frame and a pusher member, a hinge for connecting the frame with the gripper arm, said hinge being in line with the pivotal support of the gripper bar whereby the frame is not moved as the gripper bar swings back and forth, a second hinge connected with said gripper bar and extending therefrom substantially as a continuation thereof, and 115
means connected with said last mentioned hinge and with the pusher member for moving the pusher member as the gripper arm is moved to an operative position.

3. A side register for printing presses 125
comprising a supporting frame, means for hinging the frame to the gripper arm in such a manner that the gripping arm may freely move without shifting the position of the frame, a sliding rod carried by the 130

- frame, a hinged member connecting the sliding rod with the gripper arm at a point offset from the first mentioned hinge whereby as the gripper arm moves the sliding rod will be reciprocated, a toggle structure having one end connected with said sliding rod, a slide movably mounted in said frame and extending transversely thereof, means for pivotally connecting said toggle to said frame and to said slide whereby when the sliding rod is operated said slide will be moved, a pusher connected with said slide, and means connected with the frame and operated by the pusher for preventing the pusher from giving the paper engaged thereby a momentum.
4. A register guide comprising a base plate, means for adjustably connecting the base plate to the gripper bar of a printing press, a frame hinged to said plate with the pivotal point thereof in line with the pivotal point of the gripper bar, a rod hinged to said plate with a pintle offset from the pintle of the hinge carrying the frame whereby the last mentioned hinge will produce a movement of said rod and pusher member carried by said frame, means transmitting motion from the rod to the pusher member for operating the same when the press is in operation so as to cause the pusher member to move in one direction when the press is closing and move in the opposite direction when the press is opening, and means operated by the pusher member for holding a paper pushed by the pusher member in a flat condition.
5. A register guide comprising a frame carried by the gripper bar of a printing press, a pusher member carried by said means, means for operating said pusher member, said means being connected with the gripper bar and operated thereby, and means carried by said frame movable at right angles to the plane of the frame for preventing the curling of the paper operated on by said pusher member.
6. A register guide comprising a pusher member, means for holding the same in place including a frame, said pusher member having a notch therein, a spring rigidly connected at one end to said frame extending through said notch, the free end of said spring normally extending in an upward direction above the pusher member, said pusher member being movable longitudinally over the spring for pressing the spring down against the paper when the pusher member is moving over to its operative position and means connecting the pusher member with the gripper bar of a printing press for positively moving the pusher member back and forth as the press is opened and closed.
7. A side register for printing presses comprising a supporting frame, means for hinging the frame to the gripper bar of a printing press, said hinging means having its pivotal point in line with the pivotal point of the gripper bar whereby the frame will remain stationary as the parts move, a sliding rod carried by the frame, a hinge member connecting the sliding rod with the gripper bar, said last mentioned hinge member being offset from the hinge member connecting the frame with the gripper bar whereby as the gripper bar moves the rod will slide back and forth according to the movement of the gripper bar, a pusher member sliding transversely of the end of said frame, a toggle structure having one end connected with said sliding rod and the opposite end connected with said frame and said pusher member whereby when the sliding rod is operated said pusher will move.
